(57) CLAIM

The ornamental design for a light fixture, as shown and described.

DESCRIPTION

FIG. 1 is a top, right end and front view of a light fixture embodying my new design;

FIG. 2 is a top view thereof;

FIG. 3 is a front view thereof, the rear view being identical thereto;

FIG. 4 is a left end view thereof, the right end view being identical thereto; and,

FIG. 5 is a bottom view thereof.

The broken lines shown on the drawings depict portions of the light fixture that form no part of the claimed design.
